UNITED STATES PATENT OFFICE.

WILLIAM FRANK AHEARN, OF TWO RIVERS, WISCONSIN, ASSIGNOR OF ONE-HALF TO PETER GAGNON, OF SAME PLACE.

NET-LIFTING MACHINE.

SPECIFICATION forming part of Letters Patent No. 608,631, dated August 9, 1898.

Application filed November 8, 1897. Serial No. 657,783. (No model.)

To all whom it may concern:

Be it known that I, WILLIAM FRANK AHEARN, a citizen of the United States, and a resident of Two Rivers, in the county of 5 Manitowoc and State of Wisconsin, have invented certain new and useful Improvements in Net-Lifting Machines; and I do hereby declare that the following is a full, clear, and exact description thereof.

- 10 My invention has for its object to simplify, cheapen, and render more effective the net-lifting machine specifically set forth in United States Patent No. 571,033, issued November 10, 1896, to myself, assignor of one-half to 15 Peter Gagnon. Therefore said invention consists in certain peculiarities of construction and combination of parts hereinafter described, with reference to the accompanying drawings, and subsequently claimed.
- 20 Figure 1 of the drawings represents an elevation of my improved net-lifting machine, partly in section, as indicated by line 1 1 in the third figure; Fig. 2, a detail plan view illustrating an adjustable cam constituting 25 part of the machine; Fig. 3, a transverse sectional view of said machine indicated by line 3 3 in the first figure; Fig. 4, a detail elevation illustrating a clutch mechanism embodied in the aforesaid machine; Fig. 5, a 30 partly-sectional plan view that further illustrates the clutch mechanism, and Fig. 6 a detail sectional view indicated by line 6 6 in the third figure.

Referring by letter to the drawings, A represents a base of cast metal or other suitable material, having standards B rising therefrom. Mounted on the base is shown a motor C, having a pinion D thereof in mesh with a spur-wheel E, loose on a partly-hollow shaft 40 F, the latter having its bearings on the standards.

Shown fast on the shaft is a peripherally flanged disk G, engaged by a friction-band H, one end of which has the form of a sleeve b, 45 engaged by a stud c, extending laterally from the spur-wheel, the other end of this friction-band being a lug d, opposed by a set-screw e, adjustable in an arm f of a plate I, having a circular aperture therein engaged by a 50 cranked eccentric J, loose on a bearing-stem

g, having screw-thread connection with the spur-wheel stud. By suitable adjustment of the eccentric J the plate I is actuated to effect a clamp of the friction-band H on the disk G, whereby the spur-wheel is clutched with the 55 shaft to impart rotary motion thereto. While I have shown and described one form of clutch mechanism, the same result may be obtained by various other well-known types of such mechanism.

A feed-pipe K for steam is coupled to a hollow bearing for shaft F, and radial arms L of a spider fast on said shaft are in communication with the bore of the same, as clearly shown in Fig. 3. Coupled to the spider-arms 65 are pipe-arms M, having their outer ends fitted in the shanks h of forked net-guards N, the latter being connected one to another by a series of troughs P, the latter being of sheet metal or other suitable material.

The net-guard shanks are hollow beyond the outer ends of pipe-arms M, fitted therein, and leading from the hollows are lateral ports i, through which steam conveyed by said pipe-arms has its outlet. Each net-guard 70 is provided with a groove j in the direction of the troughs P, and this groove is deep enough to catch the lead and float lines of a fishing-net, but too shallow to permit the entrance of fish, leads, or floats.

Fulcrum-blocks Q for levers R are fast on the pipe-arms M, and the outer end of each lever is provided with a plunger k, that extends through an opening in a corresponding net-guard to come within the aforesaid groove 85 of the same. The working end of each plunger and the opposing surface of the corresponding net-guard are preferably corrugated, as clearly shown in Fig. 6, to thereby obtain a grip that will prevent slip of the 90 aforesaid lead and float lines of a fishing-net when the latter is being lifted by my machine.

The inner end of each lever R is preferably provided with an antifriction-roller m, that comes between cam-flanges n n' of a sleeve S 95 on the shaft F, the outermost cam-flange n being provided with lugs p, with which screws t have loose connection, these screws being adjustable in other lugs q, extending up from one of the bearings for said shaft. By ad- 100

justment of the screws the cam-flanged sleeve is moved on the shaft to regulate the grip of the plungers in connection with the aforesaid levers.

5 The innermost flange n' of sleeve S is provided with a peripheral nose r in the path of antifriction-rollers s , shown loose on the cranked inner ends of push-rods U, that move in guides r' , extending from the aforesaid fulcrum-blocks. Each push-rod is provided with a rigid collar u , and a spiral spring V under tension surrounds said push-rod intermediate of its collar and guide. The outer end of each push-rod is provided with an aperture of sufficient area to prevent cutting off the adjacent port i for escaping steam.

In connection with the base A of the machine are antifriction-rollers W X, against which an incoming fishing-net has travel.

20 In practice the machine is set up in a fishing-boat and the lead and float lines of a net are gripped in one of the guards N, the motor C started, and the spur-wheel E clutched to shaft F, after which the operation of lifting the net and running it to the hold of the boat is entirely automatic. The cam-flanges of the adjustable sleeve S are timed to cause grip of each plunger k on the net-lines when the net-guard corresponding to said plunger 25 approaches a horizontal position at that side of the boat provided with the roller or rollers W, and this grip is maintained for about one-half of one revolution of said net-guard. A plunger having been automatically retracted 30 from its grip on the lead and float lines of the net, the corresponding push-rod U will be operated against the resistance of its controlling-spring to thereby insure the discharge of said lines from the net-guard groove in 35 which they have been previously gripped.

40 The slack of the net comes in the troughs P, and the latter are deep enough to prevent said net from being affected by wind, and they also retain any fish that may escape 45 therein through the net-meshes. As the net is freed from the guards it is run over the roller X to the hold of the boat, where the fish may be conveniently handled. At any time it is desirable to stop the lifting of the 50 net it is only necessary to throw the spur-wheel E out of clutch with the shaft F, and this operation may be readily effected.

55 By circulating steam through the machine the latter may be kept warm when exposed to weather of freezing temperature, and thus the most delicate parts of said machine are kept from being clogged with ice. However, this circulation of steam was a feature of the above-mentioned patent.

60 Having thus described my invention, what I claim as new, and desire to secure by Letters Patent, is—

65 1. A net-lifting machine comprising a rotative shaft, arms radiating from the shaft, net-guards carried by the arms, reciprocat- 130
ive net-gripping plungers operative in con- junction with the guards, and automatic push-

ers operative to insure disengagement of the net from said guards.

2. A net-lifting machine comprising a rotative shaft, arms radiating from the shaft, net-guards carried by the arms, troughs connecting the guards, and reciprocative net-gripping plungers operative in conjunction with said guards. 75

3. A net-lifting machine comprising a rotative shaft, arms radiating from the shaft, net-guards carried by the arms, troughs connecting the guards, reciprocative net-gripping plungers operative in conjunction with said guards, and automatic pushers operative to insure disengagement of the net from the aforesaid guards. 80

4. A net-lifting machine comprising a shaft mounted in bearings, arms radiating from the shaft, net-guards carried by the arms, troughs connecting the guards, reciprocative net-gripping plungers operative in conjunction with said guards, automatic pushers operative to insure disengagement of the net from the aforesaid guards, and a drive mechanism having clutch connection with said shaft. 85

5. A net-lifting machine comprising a rotative shaft, arms radiating from the shaft, net-guards carried by the arms, levers fulcrumed to said arms, net-gripping plungers extending from the levers to operate in conjunction with the guards, and a lever-rocking cam adjustable on said shaft. 95

6. A net-lifting machine comprising a rotative shaft, arms radiating from the shaft, net-guards carried by the arms, levers fulcrumed to said arms, net-gripping plungers extending from the levers to operate in conjunction with the guards, pushers in guide connection with the aforesaid arms to disengage the net from said guards, and a lever-rocking pusher-actuating cam adjustable on said shaft. 100

7. A net-lifting machine comprising a rotative shaft, arms radiating from the shaft, trough-connected net-guards carried by the arms, levers fulcrumed to said arms, net-gripping plungers extending from the levers to operate in conjunction with the guards, 115 pushers in guide connection with the aforesaid arms, and a lever-rocking pusher-actuating cam adjustable on said shaft. 110

8. A net-lifting machine comprising a rotative shaft, arms radiating from the shaft, net-guards carried by the arms, levers fulcrumed to said arms, net-gripping plungers extending from the levers to operate in conjunction with the guards, a lever-actuating cam provided with a peripheral nose, and 120 spring-controlled pushers having cranked ends impinging the periphery of the cam, these pushers being in guide connection with the aforesaid arms and operative to force the net out of said guards subsequent to retraction of the plungers. 125

9. A net-lifting machine comprising a rotative shaft, arms radiating from the shaft, net-guards carried by the shaft, and recipro-

cative net-gripping plungers having corrugated working ends opposed to corrugated surfaces of the guards with which they co-operate.

- 5 10. A net-lifting machine comprising a shaft mounted in bearings, arms radiating from the shaft, trough-connected net-guards carried by the arms, reciprocative net-gripping plungers operative in conjunction with the guards, a spur-wheel loose on the shaft, a clutch for the spur-wheel and shaft, and a motor-driven pinion in mesh with said spur-wheel.
- 10 15. A net-lifting machine comprising a shaft mounted in bearings, arms radiating from the shaft, trough-connected net-guards carried by the arms, levers fulcrumed to said arms, plungers extending from the levers to operate in conjunction with the guards, pushers in guide connection with the aforesaid arms, a lever-rocking pusher-actuating cam, a spur-wheel loose on the shaft, a clutch for the spur-

wheel and shaft, and a motor-driven pinion in mesh with said spur-wheel.

12. A net-lifting machine comprising a rotative shaft, arms radiating from the shaft, 25 net-guards carried by the arms, levers fulcrumed to said arms, net-gripping plungers extending from the levers to operate in conjunction with the guards, a lever-rocking cam in loose sleeve connection with said 30 shaft, lugs on a shaft-bearing and cam-adjusting screws having their bearings in said lugs.

In testimony that I claim the foregoing I have hereunto set my hand, at Two Rivers, 35 in the county of Manitowoc and State of Wisconsin, in the presence of two witnesses.
